UNITED STATES PATENT OFFICE.

ALLAN WALTER LEWIS, OF VANCOUVER, BRITISH COLUMBIA, CANADA.

LOG CARRIER.

Application filed December 3, 1924. Serial No. 753,698.

To all whom it may concern:

Be it known that I, ALLAN WALTER LEWIS, a subject of the King of Great Britain, and a resident of the city of Vancouver, in the 5 Province of British Columbia, Canada, have invented certain new and useful Improvements in Log Carriers, of which the following is a specification.

My invention relates to improvements in 10 log carriers, with more particular reference to marine carriers by the use of which large bodies of logs may be transported with great safety, facility, and economy and with greater speed, from the loading ground to 15 the discharging point in such manner that the loss of logs which frequently occurs through breaking up in heavy weather of the rafts into which they are formed according to the practice at the present time for 20 transportation is entirely prevented.

I attain this object by the construction illustrated in the accompanying drawings in which—

Fig. 1 is a side view of the log carrier.

Fig. 2 is a side view of the carrier, in sectional elevation, through the longitudinal centre line, unloaded.

Fig. 3 is a view of the carrier similar to Fig. 2, loaded.

Fig. 4 is a plan view.

Fig. 5 is a cross sectional view taken through the line 5—5 of Fig. 3.

Fig. 6 is a cross sectional view taken in front of the after compartment bulkhead 35 a portion of which is partly broken away.

Similar figures of reference indicate similar parts throughout the several views.

The carrier consists of a floating hull 1, which may be built specially for the purpose, or may be an old hull with its construction modified to suit, having watertight compartments 2 and 3 at the bow and stern which may be filled with water through sea inlet valves 4 and 5 respectively located 40 within the compartments and controlled and operated by suitable rods 6 and 7 respectively extending above the deck and fitted with handwheels 8 and 9. The portion of the carrier between the bow and stern compartments is uncovered and forms an open hold, indicated generally by the numeral 10, which is subdivided, in the carrier illustrated, into three compartments 11, 12, and 13, by strong transverse bulkheads 14 and 15, as shown in 45 Figs. 2 and 3.

The depth of the hold 10 is preferably

about 12 feet less than the depth of the bow and stern compartments 2 and 3 and extending longitudinally over the hold on the centre line of the same with its upper side slightly above the level of the decks of compartments 60 2 and 3 is a deep girder 16 which being strongly connected at its opposite ends to the compartment bulkheads and general structure stiffens the entire carrier and also acts 65 as a communicating bridge between the fore and aft ends of the carrier. The bulkheads 14 and 15, which are non-watertight, extend at their upper edges to the underside of the girder 16 and are rigidly connected thereto 70 in any approved manner, and these bulkheads are preferably spaced so that the compartments 11, 12, and 13 are of different lengths; in the carrier shown, however, the middle and after compartments 12 and 13 75 are of the same length while the forward compartment 11 is of less length than the other two. Each compartment, however, may be of a different length to the others, which enables logs of different lengths to 80 be loaded aboard the carrier compactly and with great convenience.

The opposite sides of each of the compartments 11, 12 and 13 are stiffened by 85 means of longitudinally spaced pairs of channel bars 17—18, 19—20, and 21—22, which are laid transversely across the bottom of the respective compartments with the flange edges uppermost and carried up the 90 sides of the compartments and over the opposite edges of the same, being then carried down on the outside as at 23 for a distance of about 4 feet. It will of course be understood that these channel bars are rigidly 95 secured to the main structure in accordance with the best marine practice and not only do they act as stiffeners but the transverse portions, one of which is indicated by the numeral 24 in Fig. 5, forms supports on which the weight of the log load, in each 100 compartment is carried up clear of the bottom of the carrier proper.

Adjacent the upper edges of the hold 10 and preferably secured to the respective channels are rings 25, to each of which is 105 connected one end of a chain 26 the opposite end of which is provided with any suitable form of trip hook 26^a adapted to engage a ring 27 secured to the girder 16 and fasten the chain over the top of the 110 log load, as indicated in Fig. 5, there being one ring 27 for each chain 26.

- In order to provide for the pumping out of the water in the compartments 2 and 3 and the hold 10 a centrifugal pump 28 is mounted in compartment 3, the pump shaft 5 of which is provided with a sprocket 29 chain-connected by a chain 30 with a suitably mounted sprocket 31 which may be operated by a donkey engine 32 mounted on the after deck of the carrier, which engine 10 is provided with a suitable drum mechanism, indicated by the numeral 33, for loading the logs into the several compartments, as hereinafter described, a pair of cables 34 and 35 being wound on the drum and 15 passed at their free ends through a suitable block 36 which may be connected at will to eyed members 37, 38 and 39 secured to the girder 16 according to whichever compartment is to be loaded.
- 20 40 indicates a suction valve box within the compartment 3 connected to the suction side of the pump 28 having a valve box 41 controlling a suction pipe 42 leading along the bottom of the carrier to the forward compartment 2 and passing under the transverse channels 24 and within a longitudinally arranged channel 43, a valve box 44 controlling a pipe 45 opening into the hold 10, and a valve box 46 controlling 25 a pipe 47 opening into the compartment 3, all these valves being opened or closed as required by suitable rods 48, 49, and 50 respectively extending above deck and fitted with suitable operating handles 51, 35 52, and 53.
- 54 indicates a deck controlled valve for admitting water into the hold 10, while 55 indicates the centrifugal pump discharge pipe.
- 40 The manner in which the carrier is used may be briefly described, it being understood that when light and unloaded there is no water in either of the compartments or in the hold 10. When loading water is 45 admitted until the carrier is submerged sufficiently to bring the edge of the hold to within about one foot from the sea level, so that the logs floating alongside may be hauled over the edge of the hold, rolling 50 on the edges of the channels, by the cables 34 and 35 operated by the donkey engine without any dead lift, since they are carried up by the sea outside the hold to the height at which they are transferred into the compartment, in which they are also carried up 55 by the water therein and after the first tier is loaded the other tiers are carried up both by the tiers below and by the water in the hold in which they are floating, the hold water being gradually displaced as 60 the loading proceeds by the logs or if necessary being gradually pumped out by the centrifugal pump so that when the compartment is fully loaded it is then free from 65 water, from all of which it will be seen that

at no time during the loading is there any undue strain on the donkey or the cables as the deadweight of the logs is carried by the water both inside and outside of the hold.

70 When the loading is completed in each compartment the carrier is then towed to the discharging point, the load being secured meanwhile by the chains 26, and it should be here noted that if bad weather 75 be encountered or for other reason straining of the hull be feared due to the log load the weight of the same may be taken off the hull bottom by pumping some water into the hold to carry the log body up 80 against the chains clear of the bottom so that the same is relieved of the weight of the log load.

85 On reaching the discharging point the chains 26 are let go and water admitted into the hold and the compartments so that the logs float freely out of the hold as the carrier sinks deeper in the water, and as the carrier may be submerged to within 2 feet of the deck level to bring the hold 90 entirely under water it will be seen that every log may be readily discharged therefrom by floating it out. The carrier is then pumped out as to both compartments and the hold ready for towing back to the loading ground again, and it will be observed 95 that due to the provision of the valves pipes 42, 45 and 47 connected independently to the separate compartments 2 and 3 and the hold 10 complete control of the trimming 100 of the carrier or the respective depths to which it may be sunk for loading or unloading is obtained. It should also be noted that, if desired, the carrier may be further stiffened by passing bands 56 completely 105 around the hull in line with the bulkheads 14 and 15 and carrying the same over the girder 16.

110 From the foregoing it will be seen that I have devised a highly practical and efficient means for transporting large bodies of logs from place to place with great safety and economy.

What I claim as my invention is:—

115 1. A log carrier comprising, a hull having an open hold extending throughout the major part of its length and water-tight compartments at its ends, adapted under water admission thereinto to sink to varying depths including total submergence of the hold while remaining buoyant, said hold having spaced channels extending transversely across but clear of the bottom of the hold and continued up the sides and over its opposite edges.

120 2. A log carrier comprising, a hull having an open hold extending throughout the major part of its length and water-tight compartments at its ends, adapted under water admission thereinto to sink to varying 125 depths including total submergence of the hold while remaining buoyant, said hold having spaced channels extending transversely across but clear of the bottom of the hold and continued up the sides and over its opposite edges.

- depths including total submergence of the hold while remaining buoyant, a longitudinal girder extending centrally over the hold between the compartments, spaced 5 transverse bulkheads in the hold extending at their upper edges to the underside of the girder dividing the hold into compartments, and spaced channels in each compartment placed with their flange edges facing into 10 the compartment extending transversely across the bottom of the same continued up its opposite sides and over its opposite edges.
3. A log carrier comprising, a hull having an open hold extending throughout the major part of its length and water-tight compartments at its ends, adapted under water admission thereinto to sink to varying depths including total submergence of the hold while remaining buoyant, a longitudinal 15 girder extending centrally over the hold between the compartments provided on each side with rings at spaced intervals, spaced transverse bulkheads in the hold extending at their upper edges to the underside of the 20 said girder dividing the hold into compartments, spaced channels in each compartment placed with their flange edges facing into the compartment extending transversely across the bottom of the same continued up 25 its opposite sides and over its opposite edges, and chains secured at one end to the respective channels adjacent the upper edges of the compartments, each chain being provided at its free end with a trip hook and 30 of length to be engaged thereby to one of the aforesaid girder rings.
4. A log carrier comprising, a hull having an open hold extending throughout the major part of its length and water-tight compartments at its ends, adapted under water admission thereinto to sink to varying depths including total submergence of the hold while remaining buoyant, a longitudinal 35 girder extending centrally over the hold between the compartments provided on each side with rings at spaced intervals, spaced transverse bulkheads in the hold extending at their upper edges to the underside of said girder dividing the hold into 40 compartments, spaced channels in each compartment placed with their flange edges facing into the compartment extending transversely across the bottom of the same continued up its opposite sides and over its 45 opposite edges, chains secured at one end to the respective channels adjacent the upper edges of the compartments, each chain being provided at its free end with a trip hook and 50 of length to be engaged thereby to one of the aforesaid girder rings, means for admitting water into either of the hull end compartments or the hold, and means for pumping the water out of either compartment or the hold.
5. A log carrier comprising, a hull having an open hold extending throughout the major part of its length and water-tight compartments at its ends, adapted under water admission thereinto to sink to varying depths including total submergence of the hold while remaining buoyant, a longitudinal girder extending centrally over the hold between the compartments provided on each side with rings at spaced intervals and on 55 its upper face with longitudinally spaced eyed members with any of which a block may be connected, spaced transverse bulkheads in the hold extending at their upper edges to the underside of the girder dividing the hold into compartments, spaced channels in each compartment placed with their flanged edges facing into the compartment extending transversely across the bottom of the same continued up its opposite sides and over its opposite edges, chains secured at one end to the respective channels adjacent the upper edges of the compartment, each chain being provided at its free end with a trip hook and of length to be engaged thereby to one of the aforesaid 60 girder rings, means for admitting water into either of the hull end compartments or the hold, means for pumping the water out of either compartment or the hold, a suitably operated drum mounted on the deck of one of the end compartments, and a pair of cables wound at one end on said drum their free ends being passed through a block adapted for connection to any of the eyed members aforesaid.
6. A log carrier comprising, a hull having an open hold extending throughout the major part of its length and water-tight compartments at its ends, adapted under water admission thereinto to sink to varying depths including total submergence of the hold while remaining buoyant, said hull being provided with a longitudinal girder extending centrally of the hold between the compartments, and longitudinally spaced 65 bands passed around the hull and the girder.
7. A log carrier comprising, a hull having an open hold extending throughout the major part of its length and water-tight compartments at its ends, adapted under water admission thereinto to sink to varying depths including total submergence of the hold while remaining buoyant, said hull being provided with a longitudinal girder extending centrally of the hold between the compartments, spaced transverse bulkheads in the hold extending at their upper edges to the underside of the girder, and bands passed around the hull and the girder in 70 line with the said bulkheads.

Dated at Vancouver, B. C., this 26th day of November, 1924.

ALLAN WALTER LEWIS.
